BOTTLE CARRIER

Leroy E. Larsen, Old Greenwich, Conn., assignor to The Coca-Cola Company, New York, N. Y., a corporation of Delaware

Application February 21, 1955, Serial No. 34,586

Term of patent 14 years

(Cl. D58—5)

The figure is a view in perspective of a bottle carrier embodying my new design.

The rear and side not shown are the same as the front and side shown.

The drawing is shaded to indicate contrast in color.

I claim:

The ornamental design for a bottle carrier, as shown and described.
